UNITED STATES PATENT OFFICE.

MYRON F. HILL, OF NEW ROCHELLE, NEW YORK.

SHIP.

Application filed April 23, 1917, Serial No. 164,043. Renewed September 15, 1923.

To all whom it may concern:

Be it known that I, MYRON F. HILL, a citizen of the United States, residing at New Rochelle, in the county of Westchester and State of New York, have invented certain new and useful Improvements in Ships, of which the following is a specification.

My invention relates to ships and to a process of construction therefor.

10 The urgent necessity of providing ocean transport at the earliest possible moment, of developing raw material into the finished product in order to solve the problem of immediate transfer of food, munitions and 15 men across the ocean, and to make up for the loss of shipping due to submarine degradations make it urgently desirable to eliminate as much labor and as many mechanical processes as may be possible in the manufacture of ships.

One object is a ship cast in sections adapted to be fastened together.

A further object is to make it possible to unite ship sections by depositing welding 25 metal between the edges to unite plating and ribs into an integral body.

A further object is to so simplify the design that a single midship section may be a duplicate of many other midship sections, 30 thus simplifying designing, drafting, pattern making and molding.

A further object is to provide for a double skin or plate construction where desired.

Another object is a system of construction 35 eliminating connection metal.

Another object is to reduce the weight of all sheet metal portions by making inside surfaces corrugated or ribbed.

Another object of my invention is to provide 40 water tight air cells to render the hull more buoyant in case it should be torpedoed.

In the drawings:—

Fig. 1 shows the side elevation of a hull.

Fig. 2 shows a cross section thereof for a 45 hull having single plating.

Fig. 3 shows in plan view how sections may be united.

Fig. 4 shows a plan view of bow sections.

Fig. 5 shows an internal view of part of, 50 or a whole section.

Fig. 6 shows an edge view thereof.

Fig. 7 shows a section of a hull having a double skin or plating.

Fig. 8 shows a plan of coring.

Fig. 9 shows a section made with two core 55 sets like that shown in Figure 8.

Fig. 10 shows a plan view of such a section with upper plating removed to show the ribs.

Fig. 11 shows a rudder post section. 60

Fig. 12 shows a detail.

Fig. 13 shows a plan view of Fig. 11 with upper deck removed.

In Fig. 1 the hull is shown divided into section 5, 6, and 7, preferably electrically 65 welded together by arc welding with a metal, welding electrode into an integral hull.

The keel may be cast solid as at 8, and side portions of the plating 9 and parts of the ribs, 10, may be cast integrally therewith. 70 The sections 11 similarly cast with rib portions may be integrally united by electric arc welding to the section 8—9—10, by joints 12. Similarly other sections of the hull may be cast and united thereto. In Fig. 3, the section 13, provided with the integrally cast rib 14, may be welded to sections 6, which may also have similar ribs 15, and joints 16.

A stem section having the stem 17, and plating 18 may be welded at 19 to other 80 plates, 13 for example, similar to that in Fig. 3.

Gates at 22 (see Fig. 5) may be provided in the mould, and gates may be applied to the rib 15, to distribute the molten 85 metal. Ribs 20 and 21 may assist the flow, thus providing stronger plates more securely united to the rib 15. Such an irregular surface may be applied to all sections, preferably, though not necessarily, to 90 the inside surfaces.

The edges of all sections in a ship may be chamfered as at 23 to provide the V-shaped groove most suitable for electric welding where plates or ribs meet. 95

Fig. 7 shows a preferred form of hull. The lines 24 represent the welded joints or seams between the sections.

The sections 25, 26, 27, and 28 may represent a complete transverse division of 100

the hull. The pattern for section 25 will serve to cast all the upper rows of sections on the two sides of the hull of similar cross-sectional form, 25, 25^a, etc. and 28, 28^a, etc.

5 The pattern for section 26 will serve to cast all sections along the keel, such as 26, 26^a; 27, 27^a, etc. until the bow and stern sections are reached. Sections 26 and 27 may be cast as a single unit if desired, the 10 openings in the keel at 29 being cored. If cast separately, the middle member 30 may be a separate casting united to the other two by welding at 31 and 32.

Manholes 33 may be provided wherever 15 desired to enable the welder to crawl between the two skins to weld the edges of the ribs together. These holes may have disks welded over them and pipes may be welded through the plates so that the chambers in 20 the castings may be used for liquid fuel, ballast, or other liquid storage, a suitable pumping system being employed to fill and empty the same where desired. These chambers being air tight and water tight 25 by reason of the welded joints also provide buoyancy sufficient to largely contribute to the buoyancy of the vessel. Their subdivision longitudinally by transverse partitions assures such independence of the air chambers as will guard against flooding from 30 penetration or injury except in the immediate neighborhood of the points of penetration.

Deck sections 34 may be cast (or rolled) 35 and welded to the hull and to each other.

Bulkheads 35 may be provided, both transverse and longitudinal and welded into the ship.

Bilge keels 36 may also be integrally 40 welded and, if desired, cast hollow by suitably coring in the mould.

Hatchways 37 may be cast in the deck sections where desired in the usual way.

The hull may be provided with lower 45 deck openings 38 if desired, cast in the sections.

In Fig. 8 is shown a core for a section 26 or 27. If these two sections are cast together the right hand end of the core posts 50 39 may rest in the core forming a space 29 in the keel.

By these means a few patterns will serve 55 for castings for most of the boat. Flaws may be healed by electric welding.

In the double skin the cores may have 60 ribbed surfaces so that the invisible or inner surfaces of the double plating have the checkered ribs as shown at 40 or 41. Connecting ribs 27^a and 27^b may also be provided as shown in Figure 10. The moulds 65 may be gated at the ribs or edges or at 42, or anywhere desired, and also properly vented.

Frames for port holes 43 may be cast integral 70 in the sections wherever desired, as

well as all other details of equipment or mountings therefor capable of such treatment.

Extra strength of plating, ribs and mountings may be cast for engine foundations. Reinforcing metal may be added where needed.

Clips 44 and 45 may be cast on or electrically welded to all edges that have to register with each other to guide each other into place. These clips should be applied to the inside of the plating between the two skins and to the edges of ribs where they are to meet, but at points where the metal may be bent by the clips if not in proper registration.

The keel sections may be laid first, faired up by measurement, supported on ways by the usual means and welded together. Then the side sections may be applied, trued up by measurement and welded. Before assembly the edges of the sections may, if desired, be trued to templets or gages by hammering or bending under hydraulic presses if necessary, and the edges trimmed or cut by the oxy-acetylene flame, if mistakes occur in size. Flaws may be healed by electric welding, or by welding on patches. The rudder post 46 may be inserted upward through the hole 47 and the socket 48 thereafter fitted to the post and welded to the keel at 49.

It is generally estimated that riveted joints in ships are about 75 per cent of the strength of the plates. The plates owing to manufacturing processes are limited in area. Ship builders use as large plates as they can get. A large number of plates are employed in a single ship, resulting in a profusion of riveted joints. The result of the strains upon a ship's hull when in service is that the weakest points yield first, and the weakest points in a riveted hull are the joints; and where there is a profusion of joints, the distribution of the weakest points is so widespread that the injury at any joint is not so severe but that it can be remedied by dry docking and tightening.

By casting larger sections with integral ribs, the number and extent of joints is very greatly reduced. This is only practicable however when the joints are substantially stronger than riveted joints.

According to my invention, the desired additional strength of the joints may be attained up even to the condition of joints stronger than the plates.

The problem of joining sections of cast steel together is quite different from the problem of joining together plates of rolled steel.

Rolled steel plates have hard, smooth surfaces created by rolling.

Cast steel plates do not have such sur-

faces but have surfaces that are rough because of being molded in sand.

If it was attempted to rivet together the edges of such cast plates, the tops of the roughnesses of the plates would be brought into contact, leaving many open spaces between them and forming crevices for the introduction of water and consequent corrosion.

10 Such a joint would not be rigid but would be susceptible to "working," and a little friction in such a joint would quickly wear it loose, so that in practice the joints would have to be constantly retightened.

15 For this reason, joints between cast plates would be considerably inferior to joints between rolled plates. By welding together these sections, however, the joints instead of being weaker than riveted joints between 20 rolled plates become stronger than such joints, for cast steel welds most successfully.

The casting is preferably accomplished by employing the latest engineering principles such for example as is known as the "block 25 system" of moulding.

Rolled sheet metal sections may be welded to castings where ribs are not required for strength.

I prefer to employ a system of welding 30 providing welded joints stronger than the adjoining metal in the castings. If the joints were weaker, crystallization would be concentrated at the joints and in time disrupt them. It is recognized that the idea 35 has been suggested of building a ship by bolting together a number of cast metal sections which are provided with edge flanges bolted together. Such a ship however 40 would be subject to the disadvantage that the seams would tend to bend about the bolts and cause leaks. With the present invention the edges of the shell segments are 45 secured to each other end edge to end edge, that is directly edge to edge, without the use of flanges. By this construction the joints receive direct tensile and compression 50 stresses, so that bending stresses such as are exerted on the joints of flanged shell segments are avoided. It is to be understood 55 that the drawings are intended merely to show the general idea of one form of my invention without attempting to indicate the exact location of each stiffening rib or girder in its relation to the shell plating throughout the entire ship.

It is also to be understood that the particular form of cast steel plate shown here in detail is only one illustration of the application of my invention. Obviously the 60 castings may vary in dimensions and type to suit the requirements of any particular ship within the general principles of the invention.

Many variations lie within the scope of 65 my invention, the features of construction

shown being merely illustrative of its general character.

What I claim is:—

1. A ship hull having shell plating and internal strengthening ribs or frames composed of sections, each section comprising integral shell and frame members and adapted to be handled as a unit for and during the erection of the hull, said sections being united at their edges, the edges of the shell portions of one to the shell portions of another, and the edges of frame members of one to frame members of another to form continuous girders. 70

2. The combination claimed in claim 1, having each of the said sections formed of cast metal, and having shell and frame members cast integrally in the same mold. 80

3. The combination claimed in claim 1, comprising a plurality of sections of duplicate form. 85

4. The combination claimed in claim 2, comprising a plurality of sections of duplicate form. 90

5. The combination claimed in claim 1, having sections extending from the bilge to the rail and other sections extending from the bilge to the keel. 95

6. The combination claimed in claim 2, having sections extending from the bilge to the rail and other sections extending from the bilge to the keel. 100

7. The combination claimed in claim 1, comprising a plurality of sections of duplicate form extending from the bilge to the rail and other sections extending from the bilge to the keel. 105

8. The combination claimed in claim 2, comprising a plurality of sections of duplicate form extending from the bilge to the rail and other sections extending from the bilge to the keel. 110

9. The combination claimed in claim 1, having said frame members lying in two directions at angles to each other and having integral joints. 115

10. The combination claimed in claim 2, having said frame members lying in two directions at angles to each other and having integral joints. 120

11. The combination claimed in claim 1, comprising a plurality of sections of duplicate form, having said frame members lying in two directions at angles to each other and having integral joints. 125

12. The combination claimed in claim 2, comprising a plurality of sections of duplicate form, having said frame members lying in two directions at angles to each other and having integral joints.

13. The combination claimed in claim 5, having said frame members lying in two directions at angles to each other and having integral joints.

14. The combination claimed in claim 2, 130

having sections extending from the bilge to the rail and other sections extending from the bilge to the keel, and having said frame members lying in two directions at angles 5 to each other and having integral joints.

15. The combination claimed in claim 1, having the edges of the shell and frame members of one section welded to corresponding members of the adjoining section.

16. The combination claimed in claim 2, having the edges of the shell and frame members of one section welded to corresponding members of the adjoining section.

17. The combination claimed in claim 3, having the edges of the shell and frame members of one section welded to corresponding members of the adjoining section.

18. The combination claimed in claim 2, comprising a plurality of sections of duplicate form, having the edges of the shell and frame members of one section welded to corresponding members of the adjoining section.

19. The combination claimed in claim 1, having sections extending from the bilge to the rail and other sections extending from the bilge to the keel, and having the edges of the shell and frame members of one section welded to corresponding members of the adjoining section.

20. The combination claimed in claim 2, having sections extending from the bilge to the rail and other sections extending from the bilge to the keel, and having the edges of the shell and frame members of one section welded to corresponding members of the adjoining section.

21. The combination claimed in claim 15, having the said edges butt welded.

22. The combination claimed in claim 16, having the said edges butt welded.

23. The combination claimed in claim 17, having the said edges butt welded.

24. The combination claimed in claim 18, having the said edges butt welded.

25. The combination claimed in claim 19, having the said edges butt welded.

26. The combination claimed in claim 20, having the said edges butt welded.

27. A ship having a plurality of stand-

ardized units, each containing longitudinal and transverse stiffeners cast integrally with 55 one another, the end edge of the stiffener of one unit being joined directly to the corresponding edge of the stiffener of the adjoining unit.

28. A ship hull consisting of a plurality 60 of cast steel sections provided with horizontal stiffeners welded end edge to end edge.

29. A ship hull composed mainly of sections, 65 each section having integral shell plating and internal strengthening ribs and adapted to be handled as a unit during the building of the hull, the edges of the shell plating of one section being joined directly to the edges of the shell plating of the adjoining 70 sections.

30. A ship hull composed mainly of sections, 75 each section having integral shell plating and internal strengthening ribs and adapted to be handled as a unit during the building of the hull, the edges of the shell plating of one section being joined directly to the edges of the shell plating of the adjoining sections, said sections being formed of cast metal.

31. A ship hull composed mainly of sections, 80 each section having integral shell plating portions and internal strengthening frame members and adapted to be handled as a unit during the building of the hull, the edges of the shell plating portion of one section being joined directly to the edges of the shell plating portion of an adjoining section, said sections being formed of cast metal and the frame members of each of 85 said sections being joined to the frame members of neighboring sections.

32. A ship hull composed mainly of sections, 90 each section having integral shell plating and internal strengthening frame members and adapted to be handled as a unit during the building of the hull, the edges of the shell portions of one section being joined directly to the edges of the shell portions of the adjoining sections, said sections 95 being formed of cast metal, the frame members of each of said sections being joined to the frame members of neighboring sections directly edge to edge.

In testimony whereof I affix my signature.
MYRON F. HILL.
